Primary Examiner — Sandra Snapp*Assistant Examiner* — Gilbert B Ford(74) *Attorney, Agent, or Firm* — Botos Churchill IP Law LLP(57) **CLAIM**

The ornamental design for a blood pump catheter, as shown and described.

DESCRIPTION

FIG. 1 is a top, front, right side perspective view of a blood pump catheter according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a detail view of a portion of FIG. 1.

The dot-dash broken lines represent boundaries of the enlarged portion and forms no part of the claimed design. All other broken lines illustrate portions of the blood pump catheter that form no part of the claimed design.

1 Claim, 5 Drawing Sheets(56)
